UNITED STATES PATENT OFFICE

2,590,445

STARTING OF INTERNAL-COMBUSTION ENGINES

Clark J. Moody, New York, N. Y., assignor to California Research Corporation, San Francisco, Calif., a corporation of Delaware

Application March 13, 1950, Serial No. 149,288

18 Claims. (Cl. 123—187.5)

1

This invention relates to the starting of internal combustion engines in cold weather, and is particularly concerned with the provision of new and advantageous means for discharging starting-fluid into the engine.

Fluid, containing ethyl ether as its major component, and suitable for quickly starting internal combustion engines in frigid weather, at temperatures as low as —40° F., has been available on the market for years. The invention disclosed in my application Serial No. 33,365, filed June 16, 1948, now Patent No. 2,516,787, June 25, 1950, obviates the hazards incident to the prior practice in the storage of the inflammable and explosive starting or priming fluid. In accordance with the disclosure in that application, a charge of starting fluid, sufficient for one starting of the engine, is stored in a gelatin capsule which is discarded after a single use; such capsule being placed in a receptacle connected to the engine and ruptured by forcing a puncturing element into the capsule for discharging its contents to the interior of said engine.

The present invention provides novel and improved means for receiving a rupturable capsule containing engine-starting fluid, and for puncturing said capsule and discharging its contents into the engine. A feature of the invention resides in the provision of a compact, easily manipulable, capsule-receiving and puncturing unit which may be conveniently kept in the glove compartment of an automobile when not in use, and which may be expeditiously utilized to puncture a capsule and discharge the starting fluid into the engine when such is desired. In this way there need be no puncturing unit mounted on the automobile dash and taking up room in the passenger compartment; and instead there may be mounted on the dash a simple fitting, connected to the intake manifold of the engine, to which fitting the puncturing unit, after receiving a capsule, may be quickly applied to discharge the capsule contents and then speedily removed.

A more specific feature of the invention comprises a capsule-receiving and puncturing unit having provisions enabling the capsule to be punctured prior to applying said unit to the fitting on the dash, and for discharging the contents of the punctured capsule into said fitting when said unit is applied thereto.

Other features and advantages of the invention will be hereinafter described and claimed.

In the accompanying drawings:

Fig. 1 is a view in vertical longitudinal section, with parts in elevation, showing a capsule receiv-

2

ing and puncturing unit embodying my invention.

Fig. 2 is a fragmentary elevational view of a detail.

Fig. 3 is a view of a portion of the unit of Fig. 1, showing a plunger withdrawn to permit insertion of a capsule.

Fig. 4 is a transverse sectional view taken on line 4—4 of Fig. 3.

Fig. 5 is a view in side elevation showing a fitting on the dashboard of an automobile and connected to the intake-manifold of the engine; which fitting is adapted to receive starting-fluid from a capsule in the aforementioned puncturing unit and to transmit the same to said engine.

15 Referring to the drawings, there is shown at 11 (Fig. 5) a fitting on the dashboard 12 of an automobile, and connected through piping 13 to the intake-manifold of the engine 14. The fitting 11 may be of any desired type for normally maintaining the corresponding end of the pipe 13 closed and for opening said end when a complementary fitting on the capsule-containing unit is applied thereto. For instance, the fitting 11 may be a conventional "Alemite" fitting commonly employed on bearings and other parts of automobiles, and having a check valve therein for normally preventing access to the interior of such bearing but operable to permit grease under pressure to be projected into said bearing when a grease-gun is applied to the fitting and operated. 20 It will, of course, be understood that the fitting 11 may be located on the floor or other desired part of the automobile, instead of on the dash.

The capsule receiving and puncturing unit is designated generally at 15. It has at one end a fitting 16, complementary to the fitting 11 on the dash. Said fitting 16 may be a conventional grease-gun fitting, adapted, when applied to a fitting such as 11, to permit the fluid contents of the unit 15 to be projected through said fitting 16 into the pipe 13 and thence to the intake-manifold of the engine 14. The fitting 16 may, for instance, be of the well-known type having bayonet slots (one of which is shown at 16') for engagement with pins 11' on fitting 11, and enabling the fitting 16 to be secured to said fitting 11 when said fitting 16 is given a quarter turn. The stem 16'' of fitting 16 may conveniently be threaded into the casting 17 of the unit 15, said stem having in its end a port 16''' communicating with a bore or passage 18 in the interior of said casting 17. The lower end of said bore 18 may, as shown, be closed by a removable plug 19. Normally the passage of fluid from the bore 18 through the fitting 16 is prevented by a check

valve in said fitting, such as the valve shown at 20 which may be normally pressed by a spring 21 against an end of the port 16'', thus cutting off communication between the bore 18 and the interior of the fitting 16.

An extension 17' of the casting 17 is hollow and threaded at opposite ends. One end receives a cylindrical barrel 22, and the other a plug 23. Slidable with a close fit within the barrel 22 is a piston or plunger 24 having a rod 25 secured to a disk or handle 26 external to said barrel 22 and secured to cylindrical sleeve 27 which fits over said barrel. The inner end of said sleeve 27 may be provided with a bayonet slot 28 (Fig. 2) for receiving a pin 29 on the barrel 22. It will be apparent that, when the parts are in the positions shown in Figs. 1 and 2, the sleeve 27 is locked against movement and the piston 24 is locked in the position shown. However, by pushing inwardly slightly on the disk 26, and then rotating the latter to bring the open longitudinal portion 28' of the bayonet slot opposite pin 29, the sleeve 27 and piston 24 may be retracted into the position shown in Fig. 3. When in this position, said piston and sleeve expose an opening 30 in the wall of the barrel 22, through which opening a capsule containing starting fluid may be inserted into the interior of the barrel, between the piston 24 and a puncturing blade 31. The latter is attached to or formed integrally with a washer 31' inserted in the casting extension 17' ahead of the plug 23. As shown in Fig. 4, said washer 31' is provided with a flattened portion 31'' engaging a correspondingly flattened inner wall portion of the casting extension 17', so that the plug 23 may be unscrewed when desired without rotating the blade 31 among any accumulated capsule portions.

If desired, the outward movement of the sleeve 27 and piston 24 may be limited by a pin 32 in the barrel 22, which pin extends into a slot 33 (Fig. 3) in the sleeve 27. It will, of course, be understood that the upper or outer end of said slot 33 has a horizontal portion terminating in a slight vertical dip corresponding to the formation of the bayonet slot 28, so that the pin 32 will not prevent operation of the sleeve 27 into the position shown in Fig. 2, wherein pin 29 is engaged in a slight vertical dip extending from the horizontal portion of slot 28.

Following the retraction of the plunger 24 into the position shown in Fig. 3, and the insertion of a capsule through the opening 30, the plunger is moved inwardly, and the capsule is punctured by the blade 31. Conveniently, the plunger 24 may have a recess 34 for receiving the blade 31 so that the plunger may be moved fully inwardly into overlapping relation with the blade and thus permit shortening of the sleeve 27 and a more compact arrangement of the parts.

When the plunger 24 is moved inwardly from its position shown in Fig. 3 to that of Fig. 1, following the insertion of a capsule, through opening 30, the capsule is punctured by the blade 31 and is also crushed by the piston. The fluid contents of the capsule fill the interior of the casting extension 17' but will not enter the bore 18 until a check valve 35 is retracted. Said valve 35 may, as shown, be mounted in a hollow fitting 36 threaded into the upper portion of the bore 18, and may be normally pressed by a spring 37 to close a port 38 in the upper end of said fitting. Said port communicates with the interior of the casting extension 17', which, as above-

noted, contains the fluid contents of the punctured capsule.

For controlling the operation of the check valves 20 and 35 I provide another piston 39, movable with a close fit in a barrel 40 which is threaded at one end into the casting 17. A passage 41 provides communication between the bore 18 and the interior of said barrel 40. The rod 42 of piston 40 has at its opposite end an extension 40' threaded into a handle 43. The latter, as shown, is in the form of a pistol grip. A cylindrical sleeve 44 fits over the barrel 40 and has an end 44' provided with an opening through which projects the reduced extension 40' of piston rod 42, said sleeve end being interposed between the handle and an annular shoulder 42' on the piston rod.

A latch 45, in the form of a bell-crank lever, is pivoted at 46 on the handle 43. A projection 47' on one of the arms 47 of said latch is adapted to pass through openings in the sleeve 44 and barrel 40 when said sleeve is moved to its innermost position on said barrel. Thereby the sleeve is locked to the barrel. Said projection is maintained in locking position by a spring 48 interposed between the handle 43 and arm 49 of the latch 45.

It will readily be seen that, by grasping the handle 43 and pressing the latch arm 49 toward the handle, the operator may withdraw projection 47' from engagement with the sleeve 44 and barrel 40. The operator may then retract the handle 43, sleeve 44, and piston 39 to their outermost position; during which movement the reduction in pressure in the space between the receding piston and the valve 35 causes said valve to open and permit fluid from the punctured capsule to flow through the fitting 36 into the bore 18, and thence into the interior of the barrel 40. To limit outward movement of the piston 39 and associated parts, a stop 50 may be mounted on the barrel 40 for engagement with a longitudinal slot 51 in the sleeve 44.

Upon thereafter returning the handle 43, sleeve 44, and piston 39 to their innermost positions, shown in Fig. 1, the fluid in advance of the piston 39 is compressed, overcoming the action of the spring 21 on the check valve 20, and escapes through the fitting 16. When the sleeve 44 arrives in its innermost position, the latch 45 may be released and will again lock the sleeve and associated parts to the barrel.

When not in use, the capsule-receiving unit 15 may be conveniently kept in the automobile glove compartment. To use it, the operator first simply retracts the handle 26 and plunger 24 to the Fig. 3 position, inserts a capsule through opening 30, and returns the handle and plunger 24 to their positions shown in Fig. 1, thus puncturing and collapsing the capsule. The operator then, grasping the handle 43, applies the fitting 16 over the fitting 11 on the dash-board and gives the handle a quarter turn to lock the fittings together through the engagement of bayonet slots 16' and pins 11'. When this is done, the operator presses the latch arm 49, releasing the sleeve 44, and pulls out on the handle 43 to retract the piston 39 and draw starting fluid through the valve fitting 36 into the bore 18 and barrel 40. Following retraction of said piston 39, the operator returns the handle 43 to its Fig. 1 position, compressing the starting fluid in advance of the piston, and forcing said fluid past check valve 20, through fitting 16, into fitting 11, and thence past the check valve in said fitting 11 into pipe

13 and the engine manifold. Upon the return of handle 43 to its Fig. 1 position the latch arm 49 may be released so that said handle and sleeve 44 are again locked in that position. Following this discharge of said fluid to said manifold, the unit 15 is turned reversely to disconnect fitting 16 from said fitting 11, and is then withdrawn and returned to the glove compartment. The plug 23 may be unscrewed whenever desired to afford access to the washer 31' and blade 31, which may then be removed to clean said blade and to withdraw used-capsule fragments from the interior of the fitting 17.

The removable plug 19 enables convenient access to the valve 35 whenever desired.

The terms and expressions which I have employed are used as terms of description and not of limitation, and I have no intention, in the use of such terms and expressions, of excluding any equivalents of the features shown and described or portions thereof, but recognize that various modifications are possible within the scope of the invention claimed.

I claim:

1. A device for puncturing a starting-fluid capsule and expelling said fluid, said device comprising, in combination, a chamber for receiving a capsule, puncturing means therein, a second chamber, valve means normally preventing escape of fluid from said first to said second chamber but operable to permit such escape, means movable in one direction to cause operation of said valve means to permit such escape, a fitting connected to said second chamber, and valve means normally preventing escape of fluid from said second chamber through said fitting but operable upon actuation of said movable means in the opposite direction to permit such escape.

2. A device for puncturing a starting fluid capsule puncturing means, a second chamber for receiving fluid from the punctured capsule, a fitting communicating with said second chamber and adapted for engagement with a complementary fitting on said automobile for passing said fluid thereto, and means in said second chamber for drawing fluid from the first mentioned chamber and discharging said fluid through said fittings.

3. In combination, means for puncturing a starting-fluid capsule, a fitting adapted for engagement with a complementary fitting in communication with an automobile engine, and means for withdrawing fluid from the punctured capsule and expelling said fluid through said fittings.

4. In combination, means for puncturing a starting-fluid capsule, a fitting providing an outlet for said fluid, and means for conducting said fluid from the punctured capsule to said fitting, said fitting being adapted to telescopic engagement with and disengagement from a complementary fitting communicating with an automobile engine.

5. In combination, a chamber for receiving a starting-fluid capsule, means in said chamber for puncturing said capsule, a fitting providing an outlet for said fluid, passage means leading from said chamber to said fitting, and valve means controlling flow of fluid in said passage means, said fitting being adapted for telescopic engagement with and disengagement from a complementary fitting communicating with an automobile engine.

6. A starting-fluid capsule applicator comprising a chamber for receiving a capsule, means in said chamber for puncturing said capsule, pas-

sage means for conducting fluid from the punctured capsule away from said chamber, an outlet fitting communicating with said passage, said fitting being adapted for telescopic engagement with and disengagement from a complementary fitting communicating with an automobile engine, and reciprocable plunger means for withdrawing fluid from said chamber to said passage and forcing said fluid into said outlet fitting.

10 7. A starting-fluid capsule applicator comprising a chamber for receiving a capsule, means in said chamber for puncturing said capsule, passage means for conducting fluid from the punctured capsule away from said chamber, an outlet fitting communicating with said passage, said fitting being adapted for telescopic engagement with and disengagement from a complementary fitting communicating with an automobile engine, and a handle for transporting said applicator to said complementary fitting and applying said outlet fitting thereto.

15 8. A starting-fluid capsule applicator comprising a chamber for receiving a capsule, means in said chamber for puncturing said capsule, passage means for conducting fluid from the punctured capsule away from said chamber, an outlet fitting communicating with said passage, said fitting being adapted for telescopic engagement with and disengagement from a complementary fitting communicating with an automobile engine, and reciprocable plunger means for withdrawing fluid from said chamber to said passage and forcing said fluid into said outlet fitting, a handle attached to said plunger for reciprocating the same, and retractile means normally latching said handle to a portion of said applicator.

20 9. A starting-fluid capsule applicator comprising a chamber for receiving a capsule, means in said chamber for puncturing said capsule, passage means for conducting fluid from the punctured capsule away from said chamber, an outlet fitting communicating with said passage, said fitting being adapted for telescopic engagement with and disengagement from a complementary fitting communicating with an automobile engine, means comprising a reciprocable plunger for withdrawing fluid from said chamber to said passage and forcing said fluid through said outlet fitting, a housing surrounding said plunger and defining a chamber therefor, a handle attached to said plunger for reciprocating the same and retractile means normally latching said handle to said housing whereby the applicator may be transported by said handle to said complementary fitting and said outlet fitting engaged therewith.

25 10. A starting-fluid capsule applicator comprising a chamber for receiving a capsule, means in said chamber for puncturing said capsule, passage means for conducting fluid from the punctured capsule away from said chamber, an outlet fitting communicating with said passage, said fitting being adapted for telescopic engagement with and disengagement from a complementary fitting communicating with an automobile engine, means comprising a reciprocable plunger for withdrawing fluid from said chamber to said passage and forcing said fluid through said outlet fitting, a housing surrounding said plunger and defining a chamber therefor, a handle attached to said plunger for reciprocating the same, a sleeve attached to said plunger and surrounding said housing, and a retractile latch carried by said handle and engageable with open-

ings in said sleeve and housing when said plunger is in a predetermined position.

11. A starting-fluid capsule applicator comprising a chamber for receiving a capsule, means in said chamber for puncturing said capsule, passage means for conducting fluid from the punctured capsule away from said chamber, an outlet fitting communicating with said passage, said fitting being adapted for telescopic engagement with and disengagement from a complementary fitting communicating with an automobile engine, valve means normally preventing escape of fluid from said chamber to said passage but operable to permit such escape, other valve means normally preventing escape of fluid from said passage through said outlet fitting but operable to permit such escape, a second chamber communicating with said passage, and a plunger in second chamber movable in one direction for drawing fluid through the first valve means into said passage and in the other direction for forcing said fluid through the other valve means and said outlet fitting.

12. A starting-fluid capsule applicator comprising a chamber for receiving a capsule, means in said chamber for puncturing said capsule, passage means for conducting fluid from the punctured capsule away from said chamber, an outlet fitting communicating with said passage, said fitting being adapted for telescopic engagement with and disengagement from a complementary fitting communicating with an automobile engine, valve means normally preventing escape of fluid from said chamber to said passage but operable to permit such escape, other valve means normally preventing escape of fluid from said passage through said outlet fitting but operable to permit such escape, a second chamber communicating with said passage, and a plunger in said second chamber movable in one direction for drawing fluid through the first valve means into said passage and in the other direction for forcing said fluid through the other valve means and said outlet fitting, and a pistol-grip handle attached to said plunger for reciprocating the same.

13. A starting-fluid capsule applicator comprising a chamber for receiving a capsule, a stationary puncturing tool removably mounted adjacent one end of said chamber, a removable plug mounted in said end of said chamber, and means in said chamber movable in one direction for permitting insertion of a capsule and in the opposite direction for forcing said capsule against said tool.

14. A starting-fluid capsule applicator comprising a chamber, a puncturing tool adjacent one end of said chamber, an opening in a wall of said chamber, and means in said chamber movable in one direction to permit insertion of a capsule through said opening and in the opposite

direction for forcing said capsule against said tool.

15. A starting-fluid capsule applicator comprising a chamber, a puncturing tool adjacent one end of said chamber, an opening in a wall of said chamber, and means in said chamber movable in one direction to permit insertion of a capsule through said opening and in the opposite direction for forcing said capsule against said tool, and a sleeve surrounding said chamber and movable with said movable means.

16. A starting-fluid capsule applicator, comprising means for receiving and puncturing a capsule, an outlet fitting adapted for telescopic engagement with and disengagement from a complementary fitting communicating with an automobile engine, and pumping means for withdrawing fluid from said chamber and expelling said fluid through said outlet fitting.

17. A starting-fluid capsule applicator, comprising means for receiving and puncturing a capsule, an outlet fitting adapted for telescopic engagement with and disengagement from a complementary fitting communicating with an automobile engine, pumping means for withdrawing fluid from said chamber and expelling said fluid through said outlet fitting, and a pistol-grip handle for applying said outlet fitting to said complementary fitting and operating said pumping means.

18. A starting-fluid capsule applicator, comprising means for receiving and puncturing a capsule, an outlet fitting adapted for telescopic engagement with and disengagement from a complementary fitting communicating with an automobile engine, pumping means for withdrawing fluid from said chamber and expelling said fluid through said outlet fitting, and a pistol-grip handle for applying said outlet fitting to said complementary fitting and operating said pumping means, latching means for holding said handle locked to a portion of said applicator during application of said outlet fitting to said complementary fitting, and means actuatable by the operator for retracting said latching means prior to operation of said pumping means.
